UNITED STATES PATENT OFFICE.

SIMEON S. JACKSON, OF BOSTON, MASSACHUSETTS, ASSIGNOR, BY MESNE ASSIGNMENTS, TO THE STAFFORD COMPANY, OF READVILLE, BOSTON, MASSACHUSETTS, A CORPORATION OF MASSACHUSETTS.

FILLING-FEELER MECHANISM FOR LOOMS.

Application filed December 17, 1920. Serial No. 431,362.

To all whom it may concern:

Be it known that I, SIMEON S. JACKSON, a subject of Great Britain, residing at Hyde Park, Boston, in the county of Suffolk, State 5 of Massachusetts, have invented a certain new and useful Improvement in Filling-Feeler Mechanisms for Looms, of which the following is a specification, reference being had therein to the accompanying drawings.

10 The invention has relation to the so-called filling-feeler mechanisms which are employed in looms for the purpose of detecting when the shuttle-contained supply of weft or filling has become depleted to the 15 predetermined extent, and thereupon bringing out about action to forestall the delivery of the last end of the said supply from the shuttle and thereby avoid the production of a short pick in the cloth being woven, which 20 would render the cloth defective.

A filling-feeler mechanism comprises, ordinarily, a weft or filling-feeler, and in conjunction therewith devices which under the governance of the filling-feeler are instrumental in bringing about the action for 25 which provision is made (in some cases automatic replenishment of the weft-supply; in others, stoppage of the loom), and a so-called controller located intermediate the filling-feeler and the said devices, itself governed by the filling-feeler, and in turn controlling the said devices.

The invention is applicable to filling-feeler mechanisms of the class provided with 35 side-slipping feeler devices, i. e., feeler devices characterized by a laterally-movable feeler member which at the time of each successive feeling action is held from lateral movement, that is to say is held from movement longitudinally of the weft or filling-carrier occupying the shuttle, by engagement of the shuttle contained supply of weft or filling therewith, until the remaining portion of the said supply is too small 40 to prevent such movement, at which stage in the depletion of the supply the laterally-movable feeler member is displaced in the direction of the length of the shuttle-contained weft or filling-carrier and as a result of such displacement the change is 45 called. The general class of side-slipping feeler devices comprises two types of such devices, to either of which the present invention is applicable. These two types are,

first, the type in which the tendency of the 55 feeler member to move laterally results from forwardly-directed contact-pressure acting against a laterally offset feeling end or tip; and second, the type in which the tendency of the feeler member to move laterally is 60 due to the application of the yielding force of a spring or other convenient means at the time of the feeling action.

The general object of the invention is to provide improved means for operatively 65 combining a side-slipping feeler device with a rocking controller having a rockshaft mounted in suitable bearings and extending in a transverse direction from the outboard position which the filling-feeler is required 70 to occupy to the inboard position of the devices through which the change is called, with the outer end of said rockshaft operatively related with the filling-feeler and the inner end thereof operatively related with 75 the said devices.

The invention consists, essentially, in a filling-feeler mechanism having, intermediate a side-slipping feeler member and a rocking controller constituting elements of such 80 mechanism, a combining member, preferably a lever, which is in lateral engagement with the feeler member, along which the feeler member slides in the forward and rearward reciprocating movement thereof which takes 85 place in the feeling action, and which, when the feeler member slips sidewise, is actuated by the laterally-moving feeler member to bring about rocking of the controller and thereby the calling of a change. 90

The drawings show illustrative embodiments of the invention in feeler-mechanisms having side-slipping feeler devices of the type first mentioned. The application of the features of the invention in connection 95 with feeler devices of the second type referred to will be obvious to those skilled in the art.

In the drawings,—

Fig. 1 is a top view of certain parts at 100 one side of a loom, including a side-slipping filling-feeler of the first type, mounted in operative position upon its stand at the corresponding end of the breast-beam, the parts being shown in their normal positions. 105

Fig. 2 is a partly sectional side elevation of the said parts.

Fig. 3 is a front view of the feeler device

and associated parts, and their supports, of Figs. 1 and 2.

Fig. 4 is a top view showing a second embodiment of the invention.

5 Fig. 5 is a partly sectional elevation looking from the left in Fig. 4.

Fig. 6 is a front view of the feeler device and associated parts of Figs. 4 and 5.

Fig. 7 is a top view showing a third embodiment of the invention.

Figs. 8 and 9 are top views showing the action of the parts of Fig. 7 at different stages in the depletion of the shuttle-contained supply of weft or filling.

15 The different views of the drawings show only small portions of the breast-beam 1 and lay-beam 2 of a loom, 3 being the front-plate of the shuttle-box upon the end of the latter which is adjacent the feeler-
20 mechanism, and 4 a shuttle occupying the said shuttle-box. The said front-plate and the front-wall of the shuttle have the usual openings 3^a, 4^a, to permit entrance of the contact-portion or tip 11 of the feeler device
25 as the lay beats up, to provide for contact between the said contact-portion or tip 11 and the filling-mass 6 upon the filling-carrier 7 occupying the shuttle.

The feeler device of each of the feeler mechanisms shown in the drawings is of the construction comprising a carrier-member 8 that is movable forwardly and rearwardly in the loom, and a feeler member 9, mounted upon a pivotal stud 10 on the said carrier-member with capacity for transverse movement in a horizontal plane, and having a rearwardly projecting contact-portion 11, filling-engaging end 11^a of which is offset laterally with relation to the pivot of the feeler-member. To this lateral offsetting is due, as is well-known, the tendency of the feeler member of feeler devices of the said construction to swing around its pivot under the forwardly acting pressure of the shuttle-contents against its contact-portion in a feeling action.

50 The carrier-member 8 of each of the said mechanisms is in the usual form of a slide working in a guideway at 12^a upon a small stand 12 attached to the outer end of a main supporting stand 13 extending outward from the breast-beam. A forwardly-extending reduced extension 8^a of the slide works in a hole through an upstanding portion 12^b 55 of the forward part of stand 12. A cap or cover-plate 12^c, bridging the guideway and holding the slide down therein, is secured in place by screws 12^d, 12^d. Other forms of carrier-member and supporting means there- 60 for known in the art are adapted to be employed.

The spring-tension by which the carrier-member is held normally in its rearward position, and is returned to that position after having been pushed forward in a feeling

action, is applied in the mechanisms of Figs. 1 to 6 by means of an expanding spiral spring 14 surrounding the reduced forward extension of the slide between the body of the slide and the upstanding portion 12^b of stand 12; while in the mechanism of Figs. 7 to 9 it is applied by means of a contracting spring 14^a having its forward end connected to a block 8^b fixed by a screw 8^c upon the slide-extension 8^a, and its rear end engaged with an arm or finger 25 projecting from a collar 25^a fixed by means of a screw 25^b upon the controller-rockshaft. In each instance the spring, as usual, yields to permit the forward movement of the feeler device that is caused by pressure of the shuttle-contained filling-mass against the filling-engaging end or tip of the feeler member at the time of a feeling action, and then returns the feeler device rearwardly to its normal position as the lay moves rearwardly.

position as the lay moves rearwardly. The rocking controller that in each of these mechanisms is combined with the feeler devices comprises a rockshaft 15 that is journaled in bearings 15^a, 15^b, with which the main supporting stand 13 is provided, and an arm 16 fixed upon the inner end of the said rockshaft and connecting with the devices through which a change in the operation of the loom is called. The drawings show devices of customary character comprising a latch or dog 18 pivotally connected with an upstanding arm 19 of the usual controlling rockshaft 20, the said controlling rockshaft 20 in practice being connected operatively with the replenishing or stopping instrumentalities of the loom. In the mechanisms shown in Figs. 1 to 3 and 7 to 9, the arm 16 is connected by a link 17 to the latch or dog 18; in Figs. 4 to 6, a pin 16^a carried by the arm 16 works in a slot 18^c extending lengthwise of the latch or dog 18. The engagement of the tooth 18^b of the latch or dog 18 by the shoulder 21^a of the vibrating weft-hammer or gooseneck 21 is controlled through the agency of the rocking control-

...er. Normally, the controller holds the latch or dog clear of the path of the shoulder 21^a of the weft-hammer or gooseneck. In Figs. 1 to 6 this result is secured through the 115 action of a spiral spring 22, surrounding the controller rockshaft and having one end thereof engaged with the adjacent stand-bearing 15^a and the other end engaged with a collar 23 fixed by means of a binding screw 120 24 upon the controller rockshaft. The said spring operates torsionally with a tendency to keep the controller-rockshaft rocked into a position in which its arm and pin hold the latch or dog 18 elevated clear of the moving 125 weft-hammer or gooseneck. The tension of the spring may be varied by adjustment of the collar around the rockshaft. In Figs. 7 to 9 the contracting spiral spring 14^a already referred to, having one end thereof engaged 130

with the arm or finger 25 which projects from the collar 25^a on the controller-rockshaft, acts with the like tendency upon the controller-rockshaft.

- 5 The intermediate member, herein a lever, which operatively combines the side-slipping feeler-member and the rocking controller with each other is marked 26 in Figs. 1 to 3, and in Figs. 4 to 9 is marked 27. 10 This lever is mounted adjacent the feeler member upon a fixed pivot, marked 28 in Figs. 1 to 3 and 29 in Figs. 4 to 9. In Figs. 1 to 3, the pivot is a screw that passes through a lateral extension of the cover- 15 plate 12^c into the outer portion of stand 13; in Figs. 4 to 9 it is a stud that projects upward from the cover-plate. One arm of the lever is in lateral engagement with the feeler member, and a second arm thereof is 20 in engagement with the arm or finger 25 which is carried by the outer portion of the controller-rockshaft. The lateral engagement of the feeler member and lever with each other permits the feeler member to 25 slide backwardly and forwardly alongside the lever in the reciprocating movements of the feeler devices which occur in the operation of the mechanism. So long as in a feeling action the engagement of the shuttle- 30 contained filling-mass with the feeler-tip prevents sidewise movement of the feeler member, the latter slides past the lever without causing any change in the position of the latter. When, however, the feeler member slips sidewise in a feeling action, it operates in its lateral swinging movement to 35 actuate the lever by swinging the latter around the pivot thereof, and by reason of the engagement of the lever with the arm or finger 25 of the controller-rockshaft brings about a rocking of the controller about the axis of said rockshaft, causing the latch or dog 18 to be engaged and actuated by the weft-hammer or gooseneck to call the 40 change.

The form, construction, and relative disposition of the intermediate lever and the parts with which it is associated vary in minor respects in the different mechanisms 50 which are shown in the drawings, and may vary otherwise in practice. In the case of the feeler-mechanism of Figs. 1 to 3, the rearwardly extending arm of the lever 26 engages with the inner side of an arm or 55 crank 9^a of the feeler member, projecting forward from the pivot 10. The tension of the controller-spring 22, acting through the lever 26, operates to press the said arm or crank 9^a toward a stop 30 on carrier 8, 60 thereby turning the feeler member around said pivot 10 into the normal presentation position shown in Fig. 1, which is determined by the contact of the arm or crank 9^a with the said stop. The lever-arm which 65 engages laterally with the arm or crank has

a contacting surface extending parallel with the path of movement of the feeler-carrier 8, so that as the feeler device reciprocates the lateral pressure of the lever against the feeler member is maintained, and the position of the lever remains unchanged until in a feeling action the feeler member slips sidewise and by turning around its pivot actuates the lever to turn the controller-rockshaft and call the change. In the case 70 of the feeler-mechanisms of Figs. 4 to 9, the rearwardly-extending arm of the lever 27 makes contact with the straight outer side of a portion of the feeler member which extends rearward from the pivot 10 of the feeler member. In a feeling action, the said straight side slides past the contacting portion of the lever-arm. Fig. 4 shows the feeler member provided with a contact-screw 31 for engagement with stop 30^a on 75 the carrier 8. By adjustment of the said screw the contact-portion or tip 11^a may be caused to stand at a greater or less distance to one side of pivot 10, in the waiting or presentation position of the feeler device, and thus by varying the extent to which the contact-portion or tip is offset laterally relative to the pivot of the feeler member the 80 sensitiveness of the device in feeling may be regulated.

90 As will be perceived, the controller spring 22 or 14^a normally acts through the controller-rockshaft and the intermediate lever to keep the feeler member turned sidewise into its normal presentation position determined by the stop 30 or 30^a, and conversely the feeler member, when it slips sidewise, acts through the lever to rock the controller against the resistance of the said spring, so as thereby 95 to call the change.

100 What is claimed as the invention is,—

1. In filling-feeler mechanism of the side-slipping class, the combination with devices for bringing about a change, including a latch or dog, of a controller-rockshaft, connecting means intermediate said controller-rockshaft and said latch or dog, and a side-slipping feeler member which has a forward and rearward movement during the 110 feeling action, of an intermediate member in lateral engagement with the feeler member and also operatively combined with the controller-rockshaft and along which the feeler member slides in the said movement, and which is actuated when the feeler member slips sidewise, to bring about rocking of the controller rockshaft around its axis and thereby the calling of a change.

115 2. The combination with devices for calling a change, including a latch or dog, a 120 rocking controller in operative engagement with the said latch or dog, means whereby said controller is yieldingly actuated to maintain said latch or dog in inoperative relations, and a side-slipping feeler member 125

130

which has a forward and rearward movement during the feeling action, of a member operatively combined with the controller and also in lateral engagement with the 5 feeler member, along which the latter slides in the said movement and through which the feeler-member, when it slips sidewise, acts to bring about rocking of the controller and thereby the calling of a change.

10 3. The combination with devices for calling a change, including a latch or dog, a rocking controller in operative engagement with the said latch or dog, yieldingly actuated to maintain said latch or dog in inoperative relations, and a side-slipping feeler member which has a forward and rearward movement during the feeling action, of a lever operatively combined with the said controller and also in lateral engagement 15 with the feeler member, along which the latter slides in the said movement and through which the feeler member, when it slips sidewise, acts to bring about rocking of the controller and thereby the calling of a 20 change.

4. The combination with devices for calling a change, a controlling rockshaft therefor, yieldingly actuated to maintain such devices inoperative, the said rockshaft having 30 an arm or finger, and a side-slipping feeler member having a forward and rearward movement during the feeling action, of a lever having an arm in lateral engagement with the feeler member and along 35 which the latter slides in its forward and rearward movement, said lever actuated when the feeler member slips sidewise, and acting through operative engagement with the said arm or finger of the controlling 40 rockshaft to bring about rocking of the controlling rockshaft, and thereby the calling of a change.

5. Weft or filling-feeler mechanism comprising a spring-controlled carrier-member, 45 a side-slipping feeler member pivoted thereon and having an engaging portion, a spring-tensioned rocking controller for the devices through which a change is called, said rocking controller having an arm or finger, and a lever having one arm engaged with the said arm or finger and a second arm laterally engaged with the engaging portion of the feeler member and along 50 which the said portion slides in the reciprocating movements of the carrier, the said lever actuated by the feeler member in the side-slipping movement of the latter to rock the controller to call the change.

6. In filling-feeler mechanism for looms, 60 the combination with a feeler-member having a side-slipping movement in case of weft-deficiency, and a latch or dog pertaining to devices for bringing about a change, of a controller-rockshaft intermediate said 65 feeler-member and said latch or dog, con-

necting means through which the said rockshaft controls the said latch or dog, and a member with which the feeler-member is in lateral sliding engagement, actuated by sidewise detecting movement of the feeler- 70 member, and when thus actuated rocking the rockshaft to cause the said connecting means to place the latch or dog in position for engagement with its actuator.

7. In filling-feeler mechanism for looms, 75 the combination with a feeler-member having a side-slipping movement in case of weft-deficiency, a latch or dog pertaining to devices for bringing about a change, and a controller-rockshaft, which in a loom extends transversely of the latter, having its inner portion operatively engaged with said latch or dog, of a lever mounted to swing in a horizontal plane, having a rearwardly extending arm with which the feeler-member is in sliding engagement, and having also an arm operatively engaged with the outer portion of the controller-rockshaft. 80

8. In filling-feeler mechanism for looms, 85 the combination with a feeler-member having a side-slipping movement in case of weft-deficiency, a latch or dog pertaining to devices for bringing about a change, and a controller-rockshaft, which in a loom extends transversely of the latter, having its 90 inner portion operatively engaged with said latch or dog, and having an arm or finger upon its outer portion, of a lever mounted to swing in a horizontal plane, having a rearwardly extending arm with which the 95 said feeler-member is in sliding engagement, and having also a transversely extending arm engaged with said arm or finger of the controller-rockshaft.

9. In filling-feeler mechanism for looms, 100 the combination with a feeler-member having a side-slipping movement in case of weft-deficiency, a latch or dog pertaining to devices for bringing about a change, and a controller-rockshaft, which in a loom extends transversely of the latter, having its inner portion operatively engaged with said 105 latch or dog, and having an arm or finger upon its outer portion, of a connector-member turning upon a pivotal axis, having a 110 presser-arm which bears against one side of the feeler-member, with sliding engagement between the two members, and a second arm in operative engagement with the 115 arm or finger upon the outer portion of the controller-rockshaft, and adapted to rotate the controller-rockshaft when said connector-member is actuated by side-wise-slipping movement of the feeler-member. 120

10. In filling-feeler mechanism for looms, 125 the combination with a feeler-member having a side-slipping movement in case of weft-deficiency, a latch or dog pertaining to devices for bringing about a change, a controller-rockshaft, which extends trans- 130

versely in a loom, and means whereby the controller-rockshaft is operatively connected with said latch or dog, of a connector-member turning upon a pivotal axis having a 5 presser-arm which bears against one side of the feeler-member and a second arm engaged with the controller-rockshaft, and a spring whereby the controller-rockshaft, connector-member, and feeler-member are

held yieldingly in their normal positions 10 and the latch or dog in inoperative relationship.

In testimony whereof I affix my signature in presence of two witnesses.

SIMEON S. JACKSON.
